DELAYED AND BRIGHTENED SWEEP CIRCUIT

Robert F. Casey, Pompton Plains, N. J., assignor to Allen B. Du Mont Laboratories, Inc., Clifton, N. J., a corporation of Delaware

Application June 18, 1954, Serial No. 437,808

7 Claims. (Cl. 315—22)

This invention relates to improvements in sweep circuits as used in cathode-ray tube instruments such as are generally adapted to show an entire wave form.

An object of this invention is to provide improvements in such circuits for facilitating the display of a desired and particular portion of a wave form.

Another object of the invention is to provide improvements in such circuits which permit of the study of any portion of a wave form.

Another object of this invention is to provide cathode ray tube circuits with means for expanding the selected portion of a particular wave form to full scope for more detailed viewing.

Still another object of the invention is to provide a cathode ray tube circuit capable of intensifying the selected portion of the trace of a portion of a wave form.

Still another object is to provide a circuit by means of which it is possible to establish the selected portion of a wave form at some definite proportion of the original wave form.

These and other objects will be apparent from the following detailed disclosure of the embodiment of the invention selected for illustrative purposes herein.

In the accompanying drawings,

Figure 1 is a diagrammatic and schematic view of the circuit of this invention; and

Figure 2 is a chart showing the related wave forms at various points in said circuit.

For the purpose of clarifying the disclosure the following definitions are proposed; "upvolting" means raising a potential but not necessarily to a positive value; "downvolting" means lowering a potential but not necessarily to a negative value.

Broadly speaking this invention involves a delay circuit for cathode ray instrumentation arranged to control two electron discharge tubes, one of which provides regulation for the brightness voltage of the cathode ray tube and the other a sweep-voltage entirely independent of the initiating voltage source.

For purposes of explanation it will be assumed that a simple sawtooth voltage formation will be used both for the sweep control and the brightness control for a cathode ray tube, although those skilled in the art will readily appreciate that more complicated wave forms for these purposes may be employed.

The circuit of this invention is essentially based upon electron discharge devices with associating circuits in accordance with this invention to provide for the objects herein set forth. At 10 is diagrammatically illustrated a source of sawtooth-sweep-voltage regardless of its mode of generation, together with a source of brightness voltage output, which is characterized as being an A sweep source. This source has the usual output terminals 16 and 72 which are the A sweep output and A brightness output, as indicated in the drawing. Terminal 16 feeds a grounded potentiometer 70, the movable contact of which is connected to the control grid 22 of a triode 20 whose cathode 21 is grounded, as shown. The anode 23 is pro-

vided with proper operating potential from the positive side of a suitable source B (not shown) through a resistor in the usual manner, and this anode is also connected through a pair of series connected resistors 12 and 14 to the negative side of the B source.

A pair of triodes 30 and 40, which for the sake of description are herein sometimes referred to as the switch-tube 30 and the brightness-tube 40, have their grids 32 and 42 connected in series through an intermediate resistor 76 to the junction point of the resistors 12 and 14 and to the cathode 61 of a diode 60. The cathodes 31 and 41 are connected to ground, as shown. Anode 43 is connected to an output terminal 71, which is designated "R Brightness" output which in turn is connected to the

15 A brightness output terminal 72 and the B+ terminal by a voltage divider 80.

Anode 33 of the switch-tube 30 is connected to the control electrode 52 of a triode 50 which is the sweep-tube of the R sweep source, which is shown as a unit 20 enclosed within the dotted rectangle 73. This connection includes a grounded sweep-capacitor 74. The cathode 51 of the sweep-tube 50 is connected through the resistor 77 to the anode 63 of the rectifier diode 60 whose anode is also connected to B- through the resistor 78. Anode 53 is connected to B+ and an adjustable voltage divider 90 is shunted across the anode 53 and cathode 51 with the usual resistor in the anode lead. A voltage regulator VR of any suitable form is shunted across this voltage divider in the usual manner and the movable contact thereof is connected through a suitable resistor to the control grid 52 of the sweep-tube 50. At 75 is the R sweep output lead.

In substance, there is provided as an adjunct to the sweep supply (A sweep source) for a cathode-ray oscilloscope designed to show an entire wave form, another sweep source (R sweep source) with interconnecting circuitry, whereby a particular portion of a wave form can be selected, amplified and intensified, thereby enhancing the utility of oscilloscope instrumentation.

40 The operation of this circuit will now be described. Tube 20 comprises an inverter stage on whose control electrode 22 is applied a potential from the terminal 16 of the source 10 through a potentiometer 70. By adjusting the potentiometer 70 any desired delay in the operating effect of the A sweep-voltage can be obtained. The inverted output of the inverter tube 20 which is now a negative going voltage is applied simultaneously to the control electrodes 32 and 42 of the switch-tube 30 and the brightness-tube 40 of the R sweep source. Since the rectifier 60 at this point is non-conducting, the potentials applied to the electrodes 32 and 42 are open circuit potentials.

Brightness-tube 40 is thus cut off by the negative voltage applied to its control electrode 42, so that its anode 43 is immediately upvolted to practically the potential of the B+ terminal of the source. This increased potential appears at the R brightness output terminal 71 and at a somewhat lower value at the output terminal 72, where the A brightness voltage due only to the A sweep circuit 10 usually appears. The A sweep circuit is also provided with a brightness tube similar to the brightness tube 40 so that there is produced the brightness voltage from that circuit. It is obvious that these brightness tubes are so called because they determine the brightness voltage at the terminals 71 and 72.

60 Likewise, anode 33 is upvolted by the negative voltage applied to its control electrode 32. As a result sweep-capacitor 74 charges up and at the same time sweep-tube 50 becomes conductive because its control electrode 52 is likewise upvolted. The result is that the second sweep 70 circuit, that is the R sweep circuit, is activated and a R circuit, that is the R sweep circuit, is activated and a R

sweep-voltage appears at its output terminal 75. Here again we see the reason for calling tube 30 a switch-tube since it switches on and off the R sweep circuit.

During these operations the control electrodes 32 and 42 remain at the same open circuit potential as determined by the non-conductive rectifier 60 and the potential at anode 23 of the inverter tube 20. When sweep-tube 50 becomes more conductive its cathode 51 is upvolted by cathode follower action in following the rising potential applied to control electrode 52. The upvolt of cathode 51 causes a corresponding upvolt of anode 63 of the rectifier so that it eventually becomes conductive, that is when the potential of anode 63 exceeds the potential of cathode 61. As soon as the rectifier becomes conductive control electrodes 32 and 42 are upvolted restoring full conductivity to the brightness-tube 40 and partial conductivity to the switch-tube 30, as determined by resistors 76, 12, and 14.

When R brightness-tube 40 becomes conductive its anode 43 is downvolted, thus terminating the increase of voltage at the terminal 71. The R sweep circuit 73 however holds since any downvolt of sweep-capacitor 74 and hence control electrode 52 would also downvolt cathode 51, which action is transmitted through diode 60 to control electrode 32, which if downvolted would upvolt anode 33 to thereby charge sweep-capacitor 74 to its initial value.

However, when the initiating A sweep retraces it causes retrace of the R sweep in the following manner. On retrace control electrode 22 is quickly downvolted, reversing the previously described operation and restoring full conductivity to switch-tube 30 whose anode 33 is thereby downvolted causing sweep-capacitor 74 to discharge through it. The result is that sweep-tube 50 is cut off and eventually the circuit through the rectifier is broken, which occurs when the potential of anode 63 falls below the potential of cathode 61.

It will be recalled that switch-tube 30 had been employing the connection through the diode 60 to balance the discharge of sweep-capacitor 74 against the charging action of sweep circuit 73. Now, however, since the diode circuit has been interrupted sweep-capacitor 74 can rapidly discharge through the switch-tube 30, its upvolted control electrode 32 permitting heavier conduction. The discharge of the sweep-capacitor 74, by cutting off the sweep-tube 50, also cuts off the R sweep circuit, thus the R sweep is terminated by the A sweep.

In review it will be noted that for an interval predetermined by the setting of potentiometer 70 after the A sweep is initiated, the A sweep and A brightness voltages at the terminals 16 and 72 are unchanged. At the end of this delay interval the brightness voltage is perceptibly increased at the output terminal 71, and the R sweep circuit 73 is activated. After another interval, determined by the resistors 77 and 78, which may be adjustable as shown in the drawings, increased brightness voltage at the terminal 71 is terminated. At the end of the A sweep, the R sweep is also caused to retrace. The effects of these conditions are shown in detail in Figure 2, which could refer to the use of the invention herein disclosed in an oscilloscope.

Referring to Figure 2, curve 1 depicts a wave form under study while curve 2 represents its brightness. Curve 3 shows the R brightness voltage, while curve 4 shows the combined brightness voltages of curves 2 and 3. The R sweep appears in curve 5 with regard to time or along the wave form of curve 1. Curve 6 shows the enlarged study section which was selected and obtained by applying the R sweep instead of the A sweep to the deflection plates of the cathode ray tube. It will be understood that a switch is provided to permit connection of the horizontal deflection means of the cathode ray tube to the A or R sweep output.

Adjustment of control 70 determines the delay D so that the study section may start at any portion of the

wave form under investigation. Resistors 77 and 78, depending upon their adjustment, control the duration of the study section L and may restrict it to a desired definite percentage of the A sweep. The R sweep time-constant, as determined by the sweep-capacitor 74, and voltage divider 90 regulates the magnitude A of the deflection voltage.

The benefits to be derived from this invention are numerous. For instance, the use of the A sweep shows the entire wave form on the cathode ray tube. Using the combination of the A sweep and combination A and R brightness permits an observer to select a study section which is indicated by a brighter trace whose length may be selected at will. Switching to the R sweep and the R brightness expands the study section to utilize the entire viewing area of the cathode ray tube screen.

It will be apparent to those skilled in the art that while one embodiment of this invention has been described others will readily occur. For this reason it is preferable not to be limited to the examples herein used for illustrative purposes, but only as required by the appended claims.

What is claimed is:

1. In combination with a sweep circuit having a sawtooth output and a brightness output, the combination comprising: a second sweep circuit having a second sawtooth output and a second brightness output; a network interconnecting said brightness outputs, whereby the trace on a cathode ray tube may be intensified; means energized by said first sweep circuit for activating said second sweep circuit and said second brightness output; and means energized by said second sweep circuit for deactivating said second sweep circuit and said second brightness output, whereby said trace may be intensified for a predetermined interval which corresponds with the activation of said second sweep circuit.

2. The combination of claim 1 wherein said activating means comprises an inverter tube connected across the output of said first sweep circuit.

3. A circuit for selecting the position and length of a portion of an oscilloscope trace for increased illumination, the circuit being of the type including a first sweep circuit and a second sweep circuit, each sweep circuit having a sawtooth voltage output and a rectangular voltage brightness output; the circuit comprising, in combination, means for combining the brightness voltage outputs of the first and second sweep circuits, means for maintaining the combined brightness output at a selected level comprising a normally conductive brightness electron tube associated with said second sweep circuit, means to render said brightness electron tube non-conductive to increase the combined brightness output voltage above the selected level, means to delay the said increase of combined brightness output voltage with respect to the sawtooth sweep of the first sweep circuit to determine the position of the initial point of the intensified trace portion, said delay means comprising a normally non-conductive inverter electron tube, means for rendering said inverter tube conductive when the sawtooth output voltage of the first sweep circuit reaches a predetermined level, a switch tube in the second sweep circuit, means for rendering said switch tube operative simultaneously with said brightness tube of the second sweep circuit, means operable by said switch tube for initiating operation of the second sweep circuit, and means operable when the sawtooth voltage output of the second sweep circuit reaches a selected value for restoring conductivity to said brightness tube of the second sweep circuit to return the combined brightness voltage output to the selected level, thus determining the length of the trace portion having increased illumination.

4. A circuit for selecting the position and length of a portion of a oscilloscope trace to be more intensely illuminated and to be enlarged, the circuit being of the

type including a first sweep circuit and a second sweep circuit, each sweep circuit having a sawtooth voltage output and a brightness voltage output; the circuit comprising, in combination, means for combining the brightness voltage outputs of the first and second sweep circuits, means for maintaining the combined brightness output at a selected level comprising a normally conductive brightness electron tube specifically associated with said second sweep circuit, means to render said brightness electron tube non-conductive to increase the combined brightness output voltage above the selected level, means to delay the said increase of combined brightness output voltage with respect to the sawtooth sweep of the first sweep circuit to determine the position of the initial point of the intensified trace portion, said delay means comprising a normally non-conductive inverter electron tube, means for rendering said inverter tube conductive when the sawtooth output voltage of the first sweep circuit reaches a predetermined level, a switch tube in the second sweep circuit, means for rendering said switch tube operative simultaneously with said brightness tube of the second sweep circuit, means operable by said switch tube for initiating operation of the second sweep circuit, means operable when the sawtooth voltage output of the second sweep circuit reaches a selected value for restoring conductivity to said brightness tube of the second sweep circuit to return the combined brightness voltage output to the selected level, thus determining the length of the increased illumination trace portion, means for adjusting the time constant of the second sweep circuit to determine the length of the intensified portion of the trace, and means for maintaining the sawtooth voltage output of the second sweep circuit at said predetermined level to thereby prevent retrace.

5. A circuit for selecting the position and length of a portion of an oscilloscope trace to be more intensely illuminated and to be enlarged, the circuit being of the type including a first sweep circuit and a second sweep circuit, each sweep circuit having a sawtooth voltage output and a brightness voltage output; the circuit comprising, in combination, means for combining the brightness voltage outputs of the first and second sweep circuits, means for maintaining the combined brightness output at a selected level comprising a normally conductive brightness electron tube specifically associated with said second sweep circuit, means to render said brightness electron tube non-conductive to increase the combined brightness output voltage above the selected level, means to delay the said increase of combined brightness output voltage with respect to the sawtooth sweep of the first sweep circuit to determine the position of the initial point of the intensified trace portion, said delay means comprising a normally non-conductive inverter electron tube, means for rendering said inverter tube conductive when the sawtooth output voltage of the first sweep circuit reaches a predetermined level, a switch tube in the second sweep circuit, means for rendering said switch tube operative simultaneously with said brightness tube of the second sweep circuit, means operable by said switch tube for initiating operation of said second sweep circuit, means operable when the sawtooth voltage output of the second sweep circuit reaches a selected value for restoring conductivity to said brightness tube of the second sweep circuit to return the combined brightness voltage output to the selected level, thus determining the length of the increased illumination trace portion, means for adjusting the time constant of the second sweep circuit to determine the length of the intensified portion of the trace, means for maintaining the sawtooth voltage output of the second sweep circuit at said predetermined level to thereby prevent retrace, and means for terminating said delay of retrace of the second sweep circuit upon retrace of the first sweep circuit.

6. A circuit for selecting the position and length of a portion of an oscilloscope trace and for enlarging said

- selected portion and increasing the intensity of illumination thereof, the circuit being of a type including a first sweep circuit and a second sweep circuit, each having a sawtooth voltage sweep output and a rectangular voltage brightness output; comprising, in combination, a resistance network interconnecting said brightness voltage outputs, means including a brightness electron tube associated with said second sweep circuit for maintaining the brightness output at a selected level, said tube having a cathode, anode and control grid, an inverter electron tube, means applying the sawtooth output voltage of the first sweep circuit to said inverter tube, a switch tube having an anode, cathode and control grid, the anode-cathode circuit of said switch tube being connected in parallel with a sweep capacitor of the second sweep circuit, a connection from said inverter tube output to the grid of said switch tube, a resistor connecting said switch tube grid to said brightness tube grid, said inverter tube serving to render said switch tube and said brightness tube simultaneously non-conductive, said switch tube initiating charging of the sweep capacitor of the second sweep circuit, said brightness tube increasing the combined brightness voltage output, means to terminate the operation of said second sweep circuit and associated brightness tube when the output of said second sweep circuit reaches a predetermined level, said means comprising a voltage divider connected to the sweep output of the second sweep circuit, a diode having an anode connected to a point on said voltage divider, and a cathode connected to the control grid of said brightness tube, said diode being rendered conductive when the sweep output voltage reaches a predetermined level to thereby return said brightness tube output to its predetermined level, said diode when conductive maintaining said switch tube at a controlled conductivity to thereby delay the retrace of the second sweep circuit whereby a single cathode ray tube oscilloscope will produce an intensified illumination of a selected trace portion when the deflection plates thereof are connected to the sweep output terminals of the first sweep circuit and will enlarge and intensify said selected trace portion when the deflection plates are connected to the sweep output terminals of the second sweep circuit.
7. A circuit for selecting the position and length of a portion of an oscilloscope trace and for enlarging said selected portion and increasing the intensity of illumination thereof, the circuit being of a type including a first sweep circuit and a second sweep circuit, each having a sawtooth voltage sweep output and a rectangular voltage brightness output; comprising, in combination, a resistance network interconnecting said brightness voltage outputs, means including a brightness electron tube in said second sweep circuit for maintaining the brightness output at a selected level, said tube having a cathode, anode and control grid, an inverter electron tube, means for applying the sawtooth output voltage of the first sweep circuit to said inverter tube, a switch tube having an anode, cathode and control grid, the anode-cathode circuit of said switch tube being connected in parallel with a sweep capacitor of the second sweep circuit, a connection from said inverter tube output to the grid of said switch tube, a resistor connecting said switch tube grid to said brightness tube grid, said inverter tube serving to render said switch tube and said brightness tubes simultaneously non-conductive, said switch tube initiating charging of the sweep capacitor of the second sweep circuit, said brightness tube increasing the combined brightness voltage output, means to terminate the operation of said second sweep circuit and associated brightness tube when the output of said second sweep circuit reaches a predetermined level, said means comprising a voltage divider connected to the sweep output of the second sweep circuit, a diode having an anode connected to a point on said voltage divider and a cathode

connected to the control grid of said brightness tube, said diode being rendered conductive when the sweep output voltage reaches a predetermined level to thereby return said brightness tube output to its predetermined level, said diode when conductive maintaining said switch tube at a controlled conductivity to thereby delay the retrace of the second sweep circuit whereby a single cathode ray tube oscilloscope will produce an intensified illumination of a selected trace portion when the deflection plates thereof are connected to the sweep output terminals of the first sweep circuit and will enlarge and intensify the selected trace portion when the deflection plates are connected to the sweep output terminals of the second sweep circuit, said inverter electron tube being restored to conductivity by the decreased sweep voltage output of the first sweep circuit upon retrace, 15

8
said inverter tube then rendering said switch tube conductive and causing the second sweep circuit to retrace.
